CHARLES F. HATHAWAY, OF LOS ANGELES, CALIFORNIA.

FILTER.

1,181,762.

Specification of Letters Patent.

Patented May 2, 1916.

Application filed September 9, 1914. Serial No. 860,851.

To all whom it may concern:

Be it known that I, CHARLES F. HATHAWAY, a citizen of the United States, residing at Los Angeles, in the county of Los Angeles and State of California, have invented new and useful Improvements in Filters, of which the following is a specification.

This invention relates to filters, and more particularly to filters for handling large volumes of fluid, such as those utilized in purifying or cleansing the water supply of communities; and the invention has for its object to provide an improved filter which will be inexpensive and simple in construction, compact in form, positive and highly efficient in operation, readily cleaned or ridged of the accumulations accompanying extended periods of filtration, and which will be generally superior in efficiency and serviceability.

With the above and other objects in view, the invention consists in the novel and useful provision, formation, construction, combination, association and relative arrangement of parts, members and features, all as hereinafter described, shown in the drawing and finally pointed out in claims.

In the drawing: Figure 1 is a vertical transverse sectional view of a filter constructed in accordance with the invention, certain features thereof being shown in elevation or diagrammatically; Fig. 2 is a top plan view of the same; and, Fig. 3 is a fragmentary enlarged sectional view, being a partial showing of the matter of Fig. 1 upon an enlarged scale.

Corresponding parts in all the figures are designated by the same reference characters.

Referring with particularity to the drawing, the filter comprises in the main a filtration chamber A within a casing consisting of a vertical cylindrical shell 4 to which is applied a bottom closure 5 and a top closure 6, preferably curved or concave, respectively downwardly and upwardly, to a radius, in each instance, which is approximately the height or depth of the shell 4. The bottom closure 5 has a lapped joint over the bottom of the shell 4, and is permanently riveted thereto as at 7. The top closure 6 carries an annular angle iron 8 upon an annular flange or lip 9 which is bolted to a similar angle iron 10 connected with the top portion of the shell 4, as at 11, a gasket 12 being disposed between said angle irons to produce a tight joint between

the top closure and the shell 4. To more effectively seal this joint the lower edge of the top closure 6 and the upper edge of the shell 4 are preferably spaced slightly apart, producing a seat for a packing material or calking 13, which is massed into such seat and forced outwardly by the pressure obtaining in the filtration chamber, and supplements the action of the gasket. In the central zone of the filtration chamber is provided a filtering or separating means B. Three means of communication with the filtration chamber are preferably provided, one by means of a pipe 14 beneath the filtering means B and at one side of the filtration chamber, the second 15 at the bottom closure 5, and the third 16 above the filtration means and at one side of the filtration chamber. Both pipes 14 and 16 are coupled on to the shell 4 of the filtration chamber. These several pipes, providing outlets and inlets from and into the filtration chamber, enter materially into the preferred and advantageous mode of operation of the improved filter, and are preferably connected together, and assembled for joint use or inter-communication, by means of a by-pass or shunt pipe 17 connected with the pipes 14 and 16, and a by-pass or shunt pipe 18 connecting the pipes 15 and 16. A supply line pipe 19 communicates with the pipes 14 and 17. An outlet line pipe 20 communicates with the pipe 16. A drain pipe 21 communicates with the pipe 15 and the pipe 18. A gate valve 22 is provided in the pipe 14. A gate valve 23 is provided in the by-pass pipe 17. A gate valve 24 is provided in the outlet pipe 20. A gate valve 25 is provided in the by-pass pipe 18; and a gate valve 26 is provided in the pipe 15.

The filtration means B may, with respect to the other features of the invention, be widely varied in construction and detail organization. I have, however, disclosed in the drawing, and will now describe, a particular and meritorious filtration means which I have found in practice to be of high efficiency and particularly adapted for practising the invention as a whole. Such filtration means B preferably comprises spaced transverse perforated top and bottom walls 27 and 28, respectively, the perforations 29 of which are distributed uniformly throughout the extent of such walls, and are of sufficient size to permit of free flow of liquid through the filtration means. Each of such

walls is held in position by a plurality of knee plates 30 which are riveted to the walls 27 and 28 and fit detachably within the shell 4, the lower series of such knee plates 30 abutting against the bottom closure 5, and the upper series thereof abutting against the top closure 6, whereby when said top closure is in place it confines and holds in position both of said walls 27 and 28 together with the remaining features of the filtration means disposed between the same. Over each of said walls 27 and 28, and in the space between such walls, is laid first a course 31 of foraminous material, such as a sheet of relatively large mesh wire fabric or screen; and in superficial contact with and directly within such sheet 31 is laid a second sheet 32 of similar material of smaller mesh. Thus, the means of egress to the space between the walls 27 and 28 is gradually diminished, from the openings 29 through the openings of the successive screens of decreasing mesh. Thus, the filtration substance *b*, which is massed between the screens of the sheets 32, is held in place and prevented from escaping through the walls 27 and 28, and at the same time free passage therethrough of the liquid to be filtered is permitted, all in accordance with the density of the filtration substance *b*. Such filtration substance *b* may consist of fine gravel, charcoal, or other pulverulent or comminuted material, which may or may not have a content of medicinal or other alternative for affecting the fluid passing through the filter.

To more positively and securely hold the filtration means described within the filtration chamber, thus assisting the action of the knee plates 30, I provide a seat or ledge for the lower wall 28, the same consisting of an angle iron 33 which is riveted to and within the cylindrical shell 4 in the proper vertical zone thereof to properly station the filtration means and hold it approximately midway of the filtration chamber. Likewise, to effectively hold the top wall 27 in place, as against any surging action of the fluid passing through the filter, I provide a split holding or locking ring 34 which is introduced within the shell 4 before the top closure 6 is secured in place, and is held down firmly against the top wall 27, being provided at its ends with a threaded tightening device 35 whereby such ends may be forced apart to cause such ring to positively grip the inner walls of the shell 4.

The method of assembling, mode of operation and general advantages of the improved filter constituting the invention as hereinabove described will be readily understood from such description, taken in connection with the accompanying drawing and the following statement: In assembling the features of the filter, or means confined

within the filtration chamber A, the bottom wall 28 with its two screens 31 and 32 are first lowered into position with the knee plates 30, until such bottom wall is brought to bear upon the angle iron or ledge 33. The mass of filtration substance *b* is then introduced within the shell and spread over the bottom wall and its screens, whereupon the top wall 27 with its screens is placed upon the filtration substance, and the split holding or locking ring 34 is brought to bear upon the top wall 27 and tightened or adjusted so as to effectively hold such top wall in place and confine the filtration substance positively in position between the walls 27 and 28 and the attendant features. The top closure 6 is then placed in position and brought to bear upon the upper knee plates 30, assisting in the holding action of the locking ring 34. Thus, the tendency of the liquid pulsating or forcibly flowing through the filtration chamber to dislodge or shift or disturb any of the features of the filtration means is effectively opposed.

The water or other fluid enters the filtration chamber through the pipe 14 from the supply pipe 19, the gate valve 22 being open, the gate valve 24 being open, and the gate valves 23, 25 and 26 being closed, and rises within the filtration chamber, passing through the filtration means B, the foreign substance or substances in suspension being taken up by the filtration substance, so that as the fluid passes out at the top of the filtration means it is clear and pure and in such state flows out through the pipe 16 and the outlet pipe 20 in which the gate valve 24 is open. The action of the filter may be continuous and may be maintained for a long period of time without attention to the filtration means B or cleansing or renewing of the same or the filtration substance *b*. If now it be desired to wash out or cleanse the filtration chamber and the filtration means therein, the gate valve 22 is closed, the gate valve 24 is closed, the gate valve 25 is closed, the gate valve 26 is opened, and the gate valve 23 is opened, thus liquid enters the filtration chamber above the filtration means and is forced downwardly through the same and emerges beneath the filtration means and passes outwardly through the pipe 15 and the drain pipe 21. The man-hole or arm-hole 36, in the shell 4 beneath the filtration means, enables any collection of foreign substances or separated substances to be taken out of the chamber, such as may accumulate from time to time, or such as may remain therein after the cleansing process just described has been carried on. Now, to remove from the filtration chamber the charge of unfiltered water which remains above the filtration means after such cleansing process has been carried on, the gate 120

- valve 23 is closed, the gate valve 24 is closed, the gate valve 26 is closed, the gate valve 25 is opened and the gate valve 22 is opened, and fluid passes from the pipe 5 19 through the pipe 14 into the filtration chamber beneath the filtration means, upwardly through the filtration means, mingle with the fluid above the filtration means, and carries the same out through the 10 pipe 16 and down through the pipe 18 and away through the drain pipe 21. Now the valve 24 is opened, the valves 25 and 26 are closed, and the valve 23 is closed, and the filtration process is carried on as before. 15 In order to remove the filtration substance b, it is only necessary to remove the top closure 6, withdraw the top wall 27 with its screens, after removing the holding ring 34, take out the filtration substance and mass in 20 place thereof fresh filtration substances as required. If the walls 27 and 28 and the screens applied to the same become clogged and require washing they may be likewise withdrawn from the top or shell 4 by removing the top closure 6 and the holding ring 34.

It is manifest that the filter described may be operated for long periods of time without attention other than the cleansing and 30 washing actions which have been described and which are rendered possible by means of the peculiar arrangement and combination of pipes and valves whereby the several portions of the filtration chamber are 35 permitted to communicate with the supply pipe, the outlet pipe and the drain pipe and with each other.

High efficiency of filtration is obtained 40 in using this apparatus, and upon test I have found that a mineral content of 76/100 of a grain to a gallon of water was ridded of 70/100 of such content by passage through a filter organized in accordance with the invention.

45 It is manifest that many variations may be made in practising the invention, with

respect to the particular features and details of construction and mode of operation, without departing from a fair interpretation of the invention.

50

Having thus described my invention, I claim and desire to secure by Letters Patent:

1. A filter including a shell having an annular internal ledge projecting from the 55 side walls thereof, a pair of spaced and opposed perforated plates arranged within the shell, one of them resting upon the ledge, filtering material confined between the perforated plates, and a split ring arranged 60 within the shell and expanded into a positive engagement with the side walls thereof for coöperation with the before mentioned ledge to retain the perforated plates in proper position within the shell. 65

2. A filter including a shell having opposed end closures, one of which is removable, said shell being also provided with an interior annular ledge projecting from the side walls thereof, a pair of spaced and 70 opposed perforated plates arranged within the shell, one of them resting upon the ledge, filtering material confined between the perforated plates, a split ring arranged within the shell and expanded into a positive engagement with the side walls thereof for 75 coöperation with the before mentioned ledge to hold the two perforated plates in position, and prop arms projecting laterally from the perforated plates at points spaced 80 from the peripheries thereof, said prop arms engaging the end closures of the shell and assisting in supporting the plates in proper position.

In testimony whereof, I have signed my 85 name to this specification in the presence of two subscribing witnesses.

CHARLES F. HATHAWAY.
